BOILER

Joseph W. Putnam, Jr., Evanston, Ill., assignor to
Plibrico Jointless Firebrick Company, Chicago,
Ill., a corporation of Illinois

Application February 3, 1937, Serial No. 123,837

5 Claims. (Cl. 122—302)

This invention relates to water tube boilers, and has to do with the baffling of such boilers for controlling the flow of the gases of combustion.

My invention is directed particularly to a novel arrangement of baffles for directing flow of the gases of combustion across the water tubes in a manner conducive to ready flow of the gases and to rapid transfer of the heat from the gases to the water tubes and the water contained therein.

10 A further object is so to arrange the baffles as to assure desirable heating of the downcomer tubes, while avoiding objectionable heating thereof such as would tend to interfere with proper delivery of feed water to the mud drum.

15 Further objects and advantages will appear from the detailed description.

In the drawings:

Figure 1 is a sectional view from front to back through a boiler embodying my invention, parts 20 being broken away;

Figure 2 is a view similar to Figure 1 showing a modification of my invention; and

Figure 3 is a view similar to Figure 1 showing a second modification of my invention.

25 I have illustrated my boiler as mounted in a suitable setting 1 comprising a furnace 2, fire-wall 3, and combustion chamber 4 above the furnace. The setting may be of any suitable or preferred construction. Steam and water drums 5, 6 and 7 are suitably mounted within setting 1, at the top thereof, and are connected by three banks of tubes to a lower mud drum 8 disposed in rear of the fire-wall 3. The front bank 9 of tubes connects the mud drum 8 to the front upper drum 7, and certain of the tubes of this bank, designated 9a, are offset downwardly and forwardly to provide a slag screen. The middle bank of tubes, connecting the middle upper drum 6 to the mud drum 8, comprises a forward group 10 and a rearward group 10a of tubes, separated by a space 11 of considerable cross-sectional area, this space being provided by offsetting forwardly the mid-portions of several of the inner rows of tubes of the forward group 10 in the manner shown. The rear bank of tubes 12 connects the rear upper drum 5 to the mud drum 8, and serves as downcomers for supplying feed water from drum 5 to the mud drum, it being understood that feed water is delivered to drum 5 in a known manner. Drums 6 and 7 are connected, at their upper portions, by steam tubes 13, and the upper portions of drums 5 and 6 are connected by steam tubes 14 and 15. The front and middle upper drums 7 and 6 are connected, at their lower portions, by water circulating tubes 16, the space be-

tween these two drums being closed by refractory 17 disposed above and adjacent tubes 16. Setting 1 is provided, at the rear and adjacent the top thereof, with an outlet 18, for the products of combustion, controlled by a damper 19.

5 A baffle 20 extends from mud drum 8 upward along the front bank 9 of tubes, at the back thereof, for the major portion of the length of this bank. This baffle is provided, a short distance from its upper end, with a projection 21 extending rearward therefrom across the space between the front bank and forward group 10 of the tubes of the middle bank, this projection also extending across the forward group of the tubes of the middle bank to the space 11. A second baffle 22 10 extends from the rear of the middle upper drum 6 downward along the rear group of tubes 10a of the middle bank to a point an appreciable distance below the inner end of extension 21, and then downward and forward across the tubes of group 20 10a and space 11 and the inner four rows of tubes of group 10, thence downward and rearward across the four inner rows of tubes of group 10 and space 11 and across the tubes of group 10a. The lower portion of baffle 22 thus comprises two 15 angularly disposed elements 22a and 22b together defining a substantially V-shaped rearwardly opening baffle element. A third baffle 23 extends from rear wall 1a of setting 1 to the rear bank of tubes and part way across this latter 25 bank, substantially midway between the arms 22a and 22b defining the rearwardly opening V-shaped baffle element previously referred to. Preferably, an upper baffle 24 extends inwardly from wall 1a to within a short distance of the rear 30 bank 12 of tubes.

The furnace may be of any suitable or preferred construction, and may utilize solid, liquid, or gaseous fuel supplied thereto in an appropriate manner. The hot products of combustion flow upwardly along the tubes of the front bank, then across the tubes of this bank between the upper end of baffle 20 and drum 7, thence across the upper portions of tubes of group 10 and space 11 and across the upper portions of tubes of group 10a, reversing their direction of flow in group 10a, reversing their direction of flow in the latter group of tubes and then flowing forward across space 11 and the intermediate portions of the tubes of group 10 into the space between the latter group of tubes and the baffle 20, reversing their direction of flow in this space and thence flowing downward and rearward across the lower portion of the tubes of group 10, across space 11, and then across the lower portion of the tubes of group 10a and of the rear 35 40 45 50 55

bank 12, passing thence upwardly and forwardly across the rear bank 12 of tubes and the tubes of group 10a, then reversing and passing upwardly and rearwardly across tubes 10a and the tubes of bank 12, then upwardly along the tubes of the latter bank, and thence to the outlet 18. The path of flow of the combustion gases is indicated by the arrows. It will be noted that the baffles cause the hot combustion gases to pass back and forth across the tubes a plurality of times, which is conducive to rapid and thorough transfer of heat from the hot gases to the tubes and the water therein. The gases of combustion do not pass across the tubes of the rear bank 12 until after they have passed across the tubes of the front and middle banks a plurality of times and have delivered a large portion of their heat to these tubes and the water therein, so that such gases are relatively cool when they first pass across the rear bank of tubes. This is advantageous in that the combustion gases are used to advantage for heating to a desirable slight extent the water delivered by the tubes of the rear bank to the mud drum 8, while objectionable heating of these tubes, to such an extent as to tend to interfere with proper delivery of feed water to the mud drum, is prevented.

The baffles are so related to each other and to the drums and the banks of tubes that the net area of the space between the upper end of baffle 20 and drum 7 is more than the net area of the space between drum 6 and projection 21 of baffle 20, the net area of the latter space being less than the net area of the space between baffle 22 and the inner end of projection 21 of baffle 20. The net area of the space between the baffle 20 and the rear end of projection 21 is greater than the net area of the space between projection 21 and element 22a of baffle 22, and the net area of the space between baffle 20 and the forward end of element 22a is less than the net area of the space between baffle 22 and the rearward end of projection 21 but greater than the net area of the space between projection 21 and element 22a. The net area of the space between the rearward end of element 22b and the rear wall 1a of setting 1 is less than the net area of the space between baffle 20 and the forward end of element 22a, and is greater than the net area of the space between the forward end of baffle 23 and the rearward end of element 22a, the net area of the latter space being greater than the net area of the space between baffle 22 and the forward end of baffle 24. The baffles and associated parts thus define a passage for the combustion gases, which passage decreases in cross sectional area to the space between baffle 22 and projection 21, where the area of the passage increases, thereby permitting expansion of the gases, the cross-sectional area of the passage, in general, then decreasing to the outlet opening 18. I find that forming the passage in this manner is advantageous in that flow of the gases is retarded somewhat, while maintaining adequate velocity of flow which, in conjunction with the expansion of the gases within the middle bank of tubes, is conducive to rapid and high transfer of heat from the combustion gases to the tubes and the water contained therein.

In the modification illustrated in Figure 2, baffle 22c is provided at its lower end with a rearwardly opening baffle element of approximately flattened V shape, defined by the arms 22d and 22e and element 22f connecting the forward ends

of these arms, and baffle 23a extends across the rear bank 12 of tubes to the last row of tubes of this bank. The construction of Figure 2 is otherwise the same as that of Figure 1, and need not be described in greater detail.

The boiler of Figure 3 is mounted in a suitable setting 30 comprising a furnace 31, fire wall 32, and combustion chamber 33 above the furnace. The setting may be of any suitable or preferred construction. Steam and water drums 34 and 35 are suitably mounted within setting 30 at the top thereof, and a submerged water drum 36 is mounted in the setting adjacent the upper portion of front wall 30b thereof. The upper drums, 34, 35 and 36 are connected by three banks of tubes to a lower mud drum 37 disposed in rear of the fire wall 32. The front bank 38 of tubes connects the mud drum 37 to the water drum 36. Drum 35 is connected to mud drum 37 by a middle bank 39 of tubes, and drum 34 is connected to the mud drum 37 by a rear bank 40 of tubes, the tubes of this latter bank serving as downcomers for supplying feed water from drum 34 to the mud drum, it being understood that feed water is delivered to drum 34 in a known manner. Drums 35 and 36 are connected by a bank 41 of water tubes entering drum 35 at the lower portion thereof, and the upper portions of drums 34 and 35 are connected by rows of steam tubes 42 and 43. Setting 30 is provided, at the rear and adjacent the top thereof, with an outlet 44, for the products of combustion, controlled by a damper 45.

A baffle 46 extends from mud drum 37 upward along the front bank 38 of tubes, at the back thereof, for the major portion of the length of this bank. This baffle is provided, at its upper end, with a projection 47 extending rearward therefrom across the space between the front bank and middle bank of tubes, this projection also extending across the tubes of the middle bank. A second baffle 48 extends from the bottom of the rear upper drum 34 downward along rear bank 40, at the back of the first row of tubes of this bank, to a point an appreciable distance below the inner end of extension 47, then downward and forward across the front row of tubes of bank 40, space 49 between the banks 39 and 40 and the last three rows of tubes of bank 39, then downward a short distance between the third and fourth rows of tubes of bank 39, thence downward and rearward across the last three rows of tubes of bank 39, the lower portion of space 49 and the first or front row of tubes of rear bank 40. The lower portion of baffle 48 thus comprises two oppositely inclined arms 48a and 48b connected, at their forward ends, by an element 48c defining, with arms 48a and 48b, a rearwardly opening baffle element of approximately flattened V shape. The forward portion of drum 34 is provided with a refractory covering 50 extending from the roof of the setting to the upper end of baffle 48. A third baffle 51 extends from rear wall 30a of setting 30 to the rear bank of tubes and across this latter bank to the forward row of tubes thereof, substantially midway between the arms 48a and 48b defining the rearwardly opening baffle element of approximately flattened V shape previously referred to. Preferably, an upper baffle 52 extends inwardly from wall 30a to within a short distance of the rear bank 40 of tubes, and then upward a short distance along this bank.

The hot products of combustion flow upward along the tubes of the front bank, then across the

tubes of this bank between the upper end of baffle 46 and drum 36, and then across the tubes of the middle bank 39 between baffle 47 and drum 35 into space 49. The products of combustion then pass downward in space 49, in part along baffle 48 and the upper portions of the tubes of the front row of rear bank 40, reversing their direction of flow and passing across the tubes of middle bank 39, between baffle 47 and arm 48a of baffle 48, into space 53 between baffle 46 and the middle bank 39 of tubes. From space 53 the products of combustion pass downward across the lower portions of the tubes of the middle bank 39, between arm 48b of baffle 48 and mud drum 37, across space 49, and the lower portions of the tubes of the rear bank 40. The products of combustion then pass in reverse direction across the tubes of bank 40, between arm 48b of baffle 48 and baffle 51, into space 49 between arms 48a and 48b of baffle 48, there reversing their direction of flow and passing again across the tubes of bank 40 between baffle 51 and arm 48a of baffle 48, thence flowing upward along the tubes of bank 40 between baffles 48 and 52, and thence to the outlet 44. The path of flow of the combustion gases is indicated by the arrows. These gases are caused to pass back and forth across the banks of tubes a plurality of times, due to the baffle arrangement, which is conducive to rapid and thorough transfer of heat from the hot gases to the tubes and the water therein. The gases of combustion do not pass across the tubes of the rear bank 40 until after they have passed across the tubes of the front and the middle banks a number of times and have delivered a large portion of their heat to these tubes and the water therein, so that such gases are relatively cool when they first pass across the rear bank of tubes. The water in this rear bank of tubes is thus heated to a desirable slight extent, while avoiding objectionable heating thereof such as to tend to interfere with proper delivery of feed water to the mud drum.

The baffles are so related to each other and to the drums and the banks of tubes as to define a passage of flow for the combustion gases which, as in Figure 1, in general decreases in net cross-area from the combustion space 33 to the outlet 44, it being noted, however, that the net area of the space between the inner end of baffle element 47 and baffle 48 is greater than the net area of the space between drum 35 and baffle element 47 and the space between baffle element 47 and arm 48a of baffle 48. In this manner, the passage for the combustion gases is provided, between the inlet and the outlet thereof, with an area or space of increased net area relative to the immediately adjacent preceding and succeeding spaces, permitting of desirable expansion of the gases without objectionably interfering with or retarding flow thereof. The arrangement of the baffles and the passage for the flow of the combustion gases will be clear from Figure 3 and need not be described in greater detail.

It will be understood that, in practice, changes in construction and arrangement of parts of my invention may be resorted to without departing from the field and scope of the same, and I intend to include all such variations, as fall within the scope of the appended claims, in this application, in which the preferred form only of my invention is disclosed.

What I claims is:

1. In combination in a water tube boiler of the character described, a setting defining a furnace

and provided with a rear outlet for products of combustion, three upper drums and a lower mud drum, banks of tubes connecting said upper drums to said mud drum, the forward bank of tubes extending over said furnace, a baffle extending from said mud drum along said forward bank of tubes for the major portion of the length thereof and thence rearward across the middle bank of tubes, a second baffle extending from an upper drum downward adjacent the front of the rear bank of tubes beyond the rearward extension of said first baffle and then downward and forward and downward and rearward across said middle bank, defining a substantially V-shaped rearwardly opening baffle element, and a third baffle extending from the rear wall of said setting across the rear bank of tubes between the arms of said substantially V-shaped element.

2. In combination in a water tube boiler of the character described, a setting defining a furnace and provided adjacent its top with a rear outlet for the products of combustion, three upper steam and water drums and a lower mud drum, banks of tubes connecting said upper drums to said mud drum, the forward bank of tubes extending over said furnace, a baffle extending from the mud drum along said forward bank of tubes for the major portion of the length thereof and thence rearward part way across the middle bank of tubes, a second baffle extending from the middle upper drum downward along the middle bank of tubes beyond the rearward extension of said first baffle and then downward and forward and downward and rearward across said middle bank, defining a substantially V-shaped rearwardly opening baffle element, and a third baffle extending from the rear wall of said setting across the rear bank of tubes between the arms of said V-shaped element.

3. In combination in a water tube boiler of the character described, a setting defining a furnace and provided adjacent its top with a rear outlet for the products of combustion, three upper steam and water drums and a lower mud drum, banks of tubes connecting said upper drums to said mud drum, the forward bank of tubes extending over said furnace, a baffle extending from the mud drum along said forward bank of tubes at the back and for the major portion of the length thereof and thence part way across the middle bank of tubes, a second baffle extending from the middle upper drum downward along the middle bank of tubes at the back thereof in spaced relation to the rearward extension of said first baffle and then downward and forward and downward and rearward across said middle bank, defining a substantially V-shaped rearwardly opening baffle element, and a third baffle extending from the rear wall of said setting across the rear bank of tubes between the arms of said V-shaped element.

4. In combination in a water tube boiler of the character described, a setting defining a furnace and provided adjacent its top with a rear outlet for the products of combustion, three upper steam and water drums and a lower mud drum, banks of tubes connecting said upper drums to said mud drum, the forward bank of tubes extending over said furnace and the middle bank of tubes comprising a forward group and a rearward group with a space of considerable cross-sectional area therebetween, a baffle extending from the mud drum along said forward bank at the back and for the major portion of the length thereof and thence rearward across the forward

- group of tubes of the middle bank, a second baffle extending from the middle upper drum downward along the rearward group of tubes of the middle bank at the back thereof beyond the rearward extension of said first baffle and then downward and forward across said rearward group of tubes to and partly across said forward group of tubes and thence downward and rearward across said forward group of tubes to and across said rearward group of tubes, defining a substantially V-shaped rearwardly opening baffle element, and a third baffle extending from the rear wall of said setting across the rear bank of tubes between the arms of said V-shaped element.
13. 5. In combination in a water tube boiler of the character described, a setting defining a furnace and provided with a rear outlet for products of combustion, three upper drums and a lower mud drum, banks of tubes connecting said upper

drums to said mud drum, the forward bank of tubes extending over said furnace, a baffle extending from said mud drum along said forward bank of tubes for the major portion of the length thereof and thence rearward across the middle bank of tubes, the latter bank of tubes and the rear bank of tubes being spaced apart and providing therebetween a space of considerable cross-sectional area, a second baffle extending from the rear upper drum downward along the rear bank of tubes adjacent the front thereof beyond the rearward extension of said first baffle and then downward and forward and downward and rearward across said middle bank, defining a substantially V-shaped rearwardly opening baffle element, and a third baffle extending from the rear wall of the setting across the rear bank of tubes between the arms of said V-shaped element.

JOSEPH W. PUTNAM, JR.
